SUPPORT

Reinhold K. Klatt, Towson, and Sloan S. Sherrill, Baltimore, Md., assignors to Western Electric Company, Incorporated, New York, N. Y., a corporation of New York

Application April 10, 1942, Serial No. 438,448

2 Claims. (Cl. 248—315)

The invention relates to supports and, more particularly, to supports for electric fans or the like.

The large oscillating electric fans in general use in large factory buildings are usually mounted upon large heavy floor bases that are not very stable. In addition to being a source of noise and inefficiency due to their permitting vibration of the fan, these large floor bases are disadvantageous in that they require considerable valuable floor space.

An object of this invention is to provide supports for electric fans or the like and, more particularly, to provide supports for supporting electric fans and the like upon walls or columns.

A support for electric fans or the like embodying the invention comprises a V-shaped frame, means affixed to the frame at the apex thereof for engagement with a device to be supported by the frame, and means for securing the extremities of the arms of the frame to a supporting member.

Other features and advantages of the present invention will become apparent from the following detailed description of one embodiment thereof, when read in conjunction with the accompanying drawing in which

Fig. 1 is a side view of a support secured to a wall for holding an electric fan;

Fig. 2 is a top plan view of the support;

Fig. 3 is a rear view of the support with a portion thereof broken away; and

Fig. 4 is a top plan view of the support attached to a column.

In the particular embodiment of the invention disclosed in the accompanying drawing, a V-shaped frame 10 consisting of arms 11—11 has an apex portion 12 to which is welded a cylindrical, centrally apertured socket 14. The frame 10 is preferably constructed of pressed sheet steel, but may be made of any material having the rigidity requisite for the purpose to which the frame is put.

The arms 11—11 decrease in width from their extremities 15—15 toward the apex 12. The socket 14 is adapted to retain a hub 16 which is secured to an electric fan 18. The fan 18 may be of the oscillating type shown in Fig. 1 or of a stationary type (not shown). A set screw 19 rigidly positions the hub 16 within the socket 14. Since the hub 16 and socket 14 will vary in size with different fans, the frame 10 may be conveniently shaped by bending the apex portion 12 about the socket 14. The arms 11—11 are provided with inwardly bent flanges 20—20, which perform the dual function of increasing the longitudinal rigidity of the arms 11—11 and providing a support to which the socket 14 may be welded.

Flanges 21—21 are formed on the extremities 15—15 of the arms 11—11 for attaching the sup-

port upon a supporting wall or column. In the particular embodiment of the invention shown in Figs. 1, 2, and 3, the flanges 21—21 are bent inwardly and have a plurality of apertures 22—22 formed therein through which bolts 24—24 extend to secure the frame 10 to a wall 25.

Fig. 4 discloses an arrangement for mounting the support upon a column 26. In this arrangement the inside of the flanges 21—21 partially encircle flange portions 28—28 of the column 26. Nuts 29—29 threaded on a bolt 30 passing through holes drilled in the arms 11—11 force the arms inwardly against the flange portions 28—28 and securely mount the frame 10 thereon. A sleeve 31 surrounding the bolt 30 prevents the nuts 29—29 from being tightened so as to deform the arms 11—11. This method of attaching the bracket to a metal column eliminates the necessity of drilling the column, which latter operation is costly and weakens the column.

The support or bracket hereinabove described not only is pleasing in appearance and light in weight, but is cheap and easy to manufacture. It greatly reduces the vibration of the fan thus increasing the efficiency of the fan and decreasing the noise due to vibration. A feature of the present invention especially desirable in factory buildings where floor space is valuable, is that it occupies no floor space whatsoever. The same support may be mounted either upon a wall or upon a column merely by varying the manner of securing the support.

What is claimed is:

1. A support for electric fans or other heavy articles, which comprises a V-shaped frame, the arms of the frame being wider at the extremities than at the apex thereof, inwardly bent reinforcing flanges extending longitudinally along the arms, transverse supporting flanges on the extremities of the arms, means for removably securing the supporting flanges to a supporting member, and a centrally apertured metal member welded to the apex of the frame and to the reinforcing flanges to form a socket designed to be engaged by a device to be supported.

2. A support for electric fans or other heavy articles, which comprises a V-shaped frame having a semicircular apex, a centrally apertured, cylindrical metal member welded within the apex to form a socket designed to be engaged by a device to be supported, transverse supporting flanges formed on the extremities of the arms of the frame for partially encircling flanges of a metal column, said arms having aligned apertures therein, and a bolt inserted through the apertures for forcing the arms into close frictional engagement with the column to rigidly but removably secure the support upon the column.

REINHOLD K. KLATT.
SLOAN S. SHERRILL.
